UNITED STATES PATENT OFFICE.

ALEXANDER ALLEN, OF PHILADELPHIA, PENNSYLVANIA.

DESIGN FOR A NURSING-VEST.

SPECIFICATION forming part of Design No. 28,389, dated March 15, 1898.

Application filed October 23, 1897. Serial No. 656,218. Term of patent 7 years.

To all whom it may concern:

Be it known that I, ALEXANDER ALLEN, a citizen of the United States, residing in Philadelphia, Pennsylvania, have invented a certain new and useful Design for a Nursing-Vest, of which the following is a specification.

The essential feature of the design consists in a nursing-vest having a V-shaped low neck and a straight opening down the front of the vest from the neck, the edge of the opening having a lace embroidered border formed substantially as shown in the drawing.

The figure in the accompanying drawing is a front view of a nursing-vest, illustrating my invention.

A is the vertically-ribbed body of the vest.

a a are the armholes, having embroidery a' and ribbon a², tied in the form of a bow at a³.

B is the neck-opening, cut low in front, as

shown, and this opening is continued at B' 20 on a vertical line to a point at a considerable distance below the neck. The opening is edged with a lace border b, and at the junction of the neck-opening with the vertical opening is a ribbon b', and at the base of the 25 opening is a ribbon b², each ribbon being tied in the form of a bow.

I claim—

The design for a nursing-vest, substantially as herein described and as shown in the 30 accompanying drawing.

In testimony whereof I have signed my name to this specification in the presence of two subscribing witnesses.

ALEXANDER ALLEN.
